UNITED STATES PATENT OFFICE.

WILLIAM M. MITCHELL, OF LOUISVILLE, KENTUCKY.

ANTICREEPER FOR RAILROAD-RAILS.

1,235,492.

Specification of Letters Patent. Patented July 31, 1917.

Application filed May 7, 1917. Serial No. 166,874.

To all whom it may concern:

Be it known that I, WILLIAM M. MITCHELL, a citizen of the United States, and a resident of Louisville, county of Jefferson, and State 5 of Kentucky, have invented certain new and useful Improvements in Anticreepers for Railroad-Rails, of which the following is a specification.

The invention relates to anti-creepers or 10 rail anchors for preventing the longitudinal movement of railroad rails. To avoid cutting, perforating or otherwise weakening the rail to receive attaching rivets or the like, rail anchors now in use are held in 15 position by a friction grip of one sort or another. But it has been found difficult to provide rail anchors of this sort, which will effectively maintain their grip on the rails under all working conditions.

20 The present invention seeks to overcome the difficulties above noted and to provide a rail anchor adapted to abut against the tie and which is solidly united to the rail by welding or fusing without weakening the 25 metal body thereof. Further objects of the invention are to provide a rail anchor which can be manufactured at very low cost and which can be readily and inexpensively applied to the rails by welding or fusing.

30 The invention consists in the features of improvement hereinafter set forth, illustrated in different preferred forms in the accompanying drawings and more particularly pointed out in the appended claims.

35 In the drawings Figure 1 is a plan view of one form of the present invention. Fig. 2 is a side view thereof. Fig. 3 is an enlarged section on the line 3—3 of Fig. 1. Fig. 4 is a view similar to Fig. 3 illustrating 40 a slightly different manner of applying the rail anchor. Figs. 5 and 6 are plan views illustrating modifications. Fig. 7 is a cross section illustrating another modification.

The improved anchor is constructed of 45 forged or rolled iron or steel and is preferably of simple form comprising only a tie-abutting portion and a portion at an angle thereto extending beneath the rail base and outwardly beyond the edge portion thereof 50 and securely fused or welded to the edge portion of the rail base. Such anchors can be inexpensively made from rolled iron or steel bars of different shapes or indeed from pieces of scrap.

55 The form shown in Figs. 1 to 4 inclusive comprises a vertically disposed tie-abutting

member or flange 1 and a vertically disposed flange 2 which extends rearwardly beneath the edge of the rail base 3 and the upper part of which is welded or fused to the rail. 60 The upper part of the flange or member 2 constitutes a rail engaging portion and the main body thereof forms a brace between the tie abutting and rail engaging portions of the anchor and is preferably centrally located with reference to the tie-abutting flange 1 so that the anchor can be readily formed of a short T-bar section.

The upper rail-engaging portion of the flange or member 2 is preferably provided 70 with a shoulder 4 that extends beneath the rail base and with an upwardly projecting part or lip 5 which extends over the vertical edge face of the rail base. The anchor can be welded or fused to one of the base flanges 75 of the rail before the rail is laid, but preferably it is applied to the rail when the latter is in position in the track. When this is done a portion of the base flange of the rail adjacent the tie, is heated nearly to the 80 fusion point by a portable heating device such as an oxy-acetylene torch. The anchor is then applied in position with the member or flange 1 abutting against the tie 6 and with the shoulder 4 extending beneath and 85 in engagement with the lower horizontal face of the rail base, but preferably the inner face of the upwardly projecting portion or lip 5 is spaced to a slight extent from the adjacent vertical edge of the rail base. The 90 adjacent portions of the lip 5 and edge of the rail base are then securely fused together by a fillet of metal as indicated at *a* in Fig. 3, the metal fillet being solidly united or incorporated with the metal of the adjacent 95 portions of the rail base and anchor.

If desired, the fillet may be formed by using the oxy-acetylene torch to fuse adjacent portions of the edge of the rail base and of the lip or portion 5 of the anchor, but 100 preferably the fillet is fused in part from a steel pencil or rod and run into the space between these parts. If desired, the portion or lip 5 may be omitted and the uniting fillet formed between the edge of the rail 105 base and the horizontal face of the projecting upper edge portion of the member 2, as indicated at *a'* in Fig. 4.

In this way, the anchor is readily and solidly secured in position without in any 110 way weakening the metal body of the rail. Obviously too, the anchor is permanently

fixed to the rail so that it cannot be dislodged by expansion and contraction or by the movement of the rail away from the tie. Nor can it be dislodged by the pounding and vibration due to the passage of heavy traffic over the rail.

The anchor thus effectively prevents creeping of the rail in the direction indicated by the arrow in Fig. 2. The reaction thrust of the rail on the flange or member 1 is resisted by the flange or member 2 which forms a brace between the tie abutment and the rail engaging portion that extends beneath the edge of the rail base. Preferably, a boss *b* of metal is welded or fused to the upper face of the rail base and to the upper portion of the anchor at a point adjacent the tie. This boss may be formed in piece with the anchor before the latter is applied, but it is preferably built up when the anchor is applied by fusing a steel rod or pencil. This boss serves to aid in resisting the reaction thrust of the tie upon the anchor and thus strengthens the welded joint. Preferably also, as most plainly shown in Fig. 1, the tie-engaging abutment member 1 extends both beneath and to one side of the rail base to a substantially equal extent on opposite sides of the welded joint and the latter is thereby relieved of horizontal twisting strains.

The form shown in Fig. 5 is similar to that previously shown and described except that the tie-abutment member 7 extends on one side only of the member 2 so that the anchor can be readily formed of a section of an angle bar. The form shown in Fig. 6 is like that shown in Figs. 1 and 5 except that it is formed of a section of channel bar. The tie-abutment member 8 extends entirely beneath the rail base and the rearwardly extending flanges or members 9 are welded to the opposite side edges thereof.

Preferably as shown in Figs. 1, 5 and 6 the portions fused or welded to the edge of the rail base are beveled or inclined at their ends, so that they will engage and deflect the wheels of a derailed car that might otherwise break off and destroy the anchors.

The form shown in Fig. 7 comprises a depending tie-engaging abutment 11, a horizontal rail engaging portion or member 10 and an intermediate hollow bracing portion 12. The portion 10 extends beneath the rail base and projects outwardly beyond the edge thereof and is provided with an upturned part or lip 13 and preferably also with an integral boss 14. In applying the anchor the portion 13 is spaced slightly from the adjacent vertical edge of the rail base and is welded thereto by a fillet as indicated at *c*. The edges of the boss 14 are welded to the upper face of the rail base by fillets *d*.

It is obvious that changes may be made in

the details set forth without departure from the essentials of the invention as defined in the claims.

I claim as my invention:—

1. The combination with a rail and its supporting cross tie, of an anchor comprising an abutment arranged to engage the side of the tie and a rail-engaging portion arranged beneath and fused or welded to the edge of the rail base. 75

2. The combination with a rail and its supporting cross tie, of an anchor comprising an abutment arranged to engage the side of the cross tie, a rail-engaging portion extending rearwardly from said abutment and fused or welded to the edge of the rail base and a brace between said rail-engaging portion and said abutment. 80

3. The combination of a rail and an anchor, comprising a vertically disposed tie-engaging abutment and a rail engaging portion disposed at an angle to said abutment and united to the edge of the rail base by a welded joint, said abutment extending on opposite sides of the edge of the rail to centralize the thrust upon said joint. 85

4. The combination with a rail and its supporting cross tie, of an anchor comprising an abutment arranged to engage the side of the cross tie, a portion disposed at an angle to said abutment extending rearwardly beneath the rail and permanently united to the rail by a welded joint extending along the edge of the rail base and a bracing portion extending between said rail-engaging portion and said abutment, substantially in alinement with said welded joint. 95

5. The combination with a rail and its supporting cross tie, of an anchor comprising an abutment arranged to engage the side of the tie and a member arranged at an angle to said abutment and extending beneath the rail, said member projecting outwardly beyond the edge of the rail base and being fused or welded to said edge. 105

6. A one-piece rail anchor comprising a vertically disposed tie-abutting flange, and a rail engaging portion extending beneath the rail and projecting outwardly beyond the edge of the rail base, said projecting portion being connected to the edge of the rail base by a fused or welded joint, said anchor having a bracing portion between said rail engaging portion and said abutment. 115

7. The combination with a rail and its supporting cross tie, of an anchor comprising a tie-abutting flange and a member extending rearwardly beneath the rail and projecting outwardly beyond the edge of the rail base, said outwardly projecting portion being fillet-welded to the edge of the rail base. 120

8. The combination with a rail and its supporting cross tie, of an anchor comprising 130

ing an abutment arranged to engage the side of the cross tie and a rearwardly extending member having a portion extending upwardly over the edge of the rail base and 5 fused or welded to said edge.

9. A one-piece rail anchor comprising a tie-engaging abutment and an upper portion arranged at an angle to said abutment and comprising a part extending inwardly beneath the rail base and an upwardly projecting lip extending over and fillet welded to the edge of the rail base, said anchor having a bracing portion between said rail engaging portion and said abutment. 10

15 10. The combination with a rail and its supporting cross tie, of an anchor comprising a depending abutment arranged to engage the side of the cross tie and a rearwardly extending portion arranged beneath and fused or welded to the edge of the rail base and a boss fused or welded to the upper face of the rail base and to the upper portion of said anchor at a point adjacent the cross tie. 20

25 11. A one-piece rail anchor formed of a section of a flanged bar and comprising a vertically disposed tie-abutting flange and a vertically disposed bracing flange arranged at an angle thereto and adapted to be welded at its upper edge to the rail base. 30

35 12. A one-piece rail anchor formed of a section of a T-bar and comprising a vertically disposed tie-abutting flange and a vertically disposed bracing member extending rearwardly from the central portion of said

tie-abutting flange and adapted to be fused or welded at its upper edge to the rail base. 40

13. The combination with a rail and a rail anchor formed of a section of a flanged bar and comprising a vertically disposed tie- 45 engaging abutment and a vertically disposed rearwardly extending brace member having its upper edge portion arranged beneath and projecting outwardly beyond the edge of the rail base and fused or welded thereto. 45

14. A one-piece metal rail anchor comprising a tie-engaging abutment, an upper, rail engaging portion disposed at an angle to said abutment and permanently united to one edge portion only of the rail base 50 and a bracing portion between said abutment and said rail-engaging portion. 50

15. A one-piece forged metal rail anchor comprising a tie-engaging abutment and an upper rail engaging portion arranged at 55 an angle to said abutment and having an inwardly projecting shoulder adapted to extend beneath the rail base and an upwardly projecting lip adapted to extend over and be fused or welded to one edge of the rail base. 60

16. A one-piece rail anchor adapted to be fused or welded to the rail base, said anchor being formed of a section of a flanged bar and comprising a vertically disposed, tie-engaging abutment and a vertically disposed brace arranged at an angle to said 65 abutment and adapted to extend beneath and engage the lower face of the rail base. 65
